(57) **CLAIM**

The ornamental design for a dual chamber condiment container, as shown and described.

DESCRIPTION

FIG. 1 is a perspective view of a first embodiment of a dual chamber condiment container showing my new design;

FIG. 2 is an exploded top left front perspective view thereof;

FIG. 3 is an exploded bottom right rear perspective view

thereof;

FIG. 4 is a front elevational view thereof;

FIG. 5 is a rear elevational view thereof;

FIG. 6 is a right elevation view thereof;

FIG. 7 is a left elevation view thereof.

FIG. 8 is a top plan view thereof;

FIG. 9 is a bottom plan view thereof;

FIG. 10 is a perspective view of a second embodiment of a dual chamber condiment container showing my new design;

FIG. 11 is an exploded top left front perspective view thereof;

FIG. 12 is an exploded bottom right rear perspective view thereof;

FIG. 13 is a front elevational view thereof;

FIG. 14 is a rear elevational view thereof;

FIG. 15 is a right elevational view thereof;

FIG. 16 is a left elevational view thereof;

FIG. 17 is a top plan view thereof; and,

FIG. 18 is a bottom plan view thereof.
